COIN RELEASE MECHANISM FOR VENDING MACHINES

Original Filed Jan. 23, 1931

INVENTOR
SAM H. SABIT
BY *Ernest B. W.*
ATTORNEY

UNITED STATES PATENT OFFICE

SAM H. SABIT, OF DETROIT, MICHIGAN

COIN RELEASE MECHANISM FOR VENDING MACHINES

Application filed January 23, 1931, Serial No. 510,637. Renewed May 27, 1932.

This invention relates to coin release mechanisms for vending machines and the object of the invention is to provide a coin release mechanism including a locking partition and a slide for carrying the coin and arranged so that when a coin is positioned in the slide, the locking partition is moved out of normal locking position by movement of the slide to allow ejection of a package from the vending machine by movement of the slide.

Another object of the invention is to provide a locking partition slidably mounted on vertical guide rods and provided with portions adapted to engage against shoulders on the slide to prevent movement of the slide, the said partition being provided with a tongue under which the coin is moved by movement of the slide to raise the partition out of locking position.

A further object of the invention is to provide a device of the character described in which the tongue will eject the coin from the slide upon return movement of the slide back to the normal position.

These objects and the several novel features of the invention are hereinafter more fully described and claimed and the preferred form of construction by which these objects are attained is shown in the accompanying drawing in which—

Fig. 1 is a perspective view of a coin release mechanism embodying my invention and in position for operation.

Fig. 2 is a similar perspective view illustrating the ejection of the coin from the slide by return movement of the slide after the mechanism has been released by the coin.

The device comprises a slide bar 1 having an upwardly extending handle 2 at the outer end thereof, a package ejection member 3 is secured to the bar 1 and is adapted to eject a package from a vending machine upon movement of the slide bar. The slide bar extends beneath a movable partition 4 which is provided with ends 5 engaging about the vertical guide rods 6. By means of the ends 5, the partition 4 may be moved up or down on the guide rods. A tongue 7 is pressed out of the metal of the partition 4 and forms shoulders 8 on each side of the tongue open-

ing which are adapted to engage against the shoulders 9 on the portion 10 of the slide bar. The portion 10 is provided with a coin slot 11 and the walls 12 of this slot extend outwardly on a curve as shown. At the discharge end of the slot 11, the slide bar is ground in an arc at 13 onto which the coin 1 is adapted to roll as it is discharged from the coin slot 11. When the coin is removed from the slot in the position shown in Fig. 1, the slide bar 1 may be withdrawn to the right of Fig. 1 by grasping the handle 2 at which time, the tongue 7 will ride on the walls 12 of the slot 11 tending to raise the partition 4 upwardly but the shoulders 8 on the partition 4 will engage against the shoulders 9 of the slide bar and prevent or limit further movement of the slide bar. By this arrangement, the device is locked from operation and will remain locked until a coin is delivered into the coin slot 11. The coin may be delivered into this slot in any suitable manner such as by means of a coin guide or other suitable mechanism.

When the coin is positioned in the slot 11 as shown in dotted lines in Fig. 1, the slide bar 1 may be withdrawn to the right of Fig. 1 at which time, the tongue 7 will ride up on the edges 12 of the slot 11 and as the coin extends slightly above the edges of the slot 11, as shown, it engages the tongue 7 and raises the shoulders 7 of the partition 4 above the shoulders 9 of the slide bar so that the remainder of the slide bar may be withdrawn beneath the partition 4 to allow ejection of a package by means of the ejection member 3. After the package has been ejected, the slide bar may be returned to its normal position either by hand by means of the handle 2 or by means of a spring attached to the opposite end of the slide bar. As the slide bar is returned to position, the tongue 7 engages the coin and moves it down onto the portion 13 of the slide bar at which time, it will fall to the dotted position indicated at 14 in Fig. 2. In order to insure the coin falling to this side of the slide bar, a plate 15 is provided which is secured in fixed relation with the guide rods 6 and prevents the coin from falling to the opposite side of the slide bar. By the ar-

arrangement shown, the tongue 7 rides on the top of the slide bar at all times as the partition 4 will slide down on the vertical guide bars 6 by gravity and the partition will be moved up off from the slide bar only by the coin which unlocks the device.

From the foregoing description, it becomes evident that the device is very simple and efficient in operation, will not easily get out of order, is composed of few parts and is of consequent low manufacturing cost and provides a device which accomplishes the objects described.

Having thus fully described my invention, its utility and mode of operation, what I claim and desire to secure by Letters Patent of the United States is—

1. In a coin release mechanism for vending machines, a slide bar having a coin slot therein and arranged to carry a coin, a vertically movable partition mounted over the slide bar, a tongue extending from the partition and riding on the surface of the slide bar, the edges of the coin slot being curved and the coin extending slightly above the curved edges of the coin slot, the arrangement being such that upon withdrawal of the slide bar the coin engages the tongue and raises the partition above the slide bar and upon return movement of the slide bar, the tongue discharges the coin from the coin slot and means limiting outward movement of the slide bar beneath the partition after the slide bar has been returned to normal position.

2. In a coin release mechanism for vending machines, a slide bar having a coin slot therein, a vertically movable partition mounted over the slide bar, a tongue extending from the partition and riding on the slide bar, the slide bar being provided with a pair of shoulders and the partition being provided with a pair of shoulders each side of the tongue adapted to be engaged by the shoulders of the slide bar to limit movement of the slide bar, the arrangement being such that upon positioning of a coin in the coin slot withdrawal of the slide bar will raise the partition to allow complete withdrawal of the slide bar beneath the partition.

3. In testimony whereof I sign this specification.

SAM H. SABIT.
